Ralph A. Millermaster, Whitefish Bay, and Alex A. Writzmann, Milwaukee, Wis., assignors to Cutler-Hammer, Inc., Milwaukee, Wis., a corporation of Delaware

Application August 26, 1943, Serial No. 111,000

Term of patent 14 years

To all whom it may concern:

Be it known that we, Ralph A. Millermaster and Alex A. Writzmann, both citizens of the United States and residents of Whitefish Bay and Milwaukee, respectively, in the county of Milwaukee and State of Wisconsin, have invented a new, original, and ornamental Design for a Fuse Holder, of which the following is a specification, reference being had to the accompanying drawing, forming part thereof.

Figure 1 is an end elevational view of a fuse holder, showing our new design.

Fig. 2 is a side elevational view of the article shown in Fig. 1.

Fig. 3 is a perspective view of the article shown in Fig. 1, and

Fig. 4 is a top plan view of the article shown in Fig. 1.

We claim:

The ornamental design for a fuse holder, as shown.

RALPH A. MILLERMASTER.
ALEX A. WRITZMANN.
